(57) **CLAIM**

The ornamental design for a wine bottle and accessory holder, as shown and described.

DESCRIPTION

FIG. 1 is a perspective view of one embodiment of the present invention;

FIG. 2 is a rear elevational view of the embodiment shown in FIG. 1;

FIG. 3 is a right side elevational view of the embodiment shown in FIG. 1, the left side being a mirror image thereof;

FIG. 4 is a front elevational view of the embodiment shown in FIG. 1;

FIG. 5 is a top plan view of the embodiment shown in FIG. 1;

FIG. 6 is a bottom plan view of the embodiment shown in FIG. 1;

FIG. 7 is a perspective view of a second embodiment of the present invention, showing the bottom drawer in an open position;

FIG. 8 is a rear elevational view of the embodiment shown in FIG. 7;

FIG. 9 is a right side elevational view of the embodiment shown in FIG. 7, the left side being a mirror image thereof;

FIG. 10 is a front elevational view of the embodiment shown in FIG. 7;

FIG. 11 is a top plan view of the embodiment shown in FIG. 7; and,

FIG. 12 is a bottom plan view of the embodiment shown in FIG. 7.

The dotted lines in FIGS. 1–3 and 5–9, 11, and 12 are for illustrative purposes only and do not form a part of the claimed design.

The broken lines and shading in FIGS. 1–12 are for illustrative purposes only and form no part of the claimed design.
